[57] CLAIM

The ornamental design for a skibinding, as shown.

DESCRIPTION

FIG. 1 is a perspective view of a skibinding in a locked position showing my new design;

FIG. 2 is a side elevational view thereof;

FIG. 3 is a perspective view thereof in a released condition;

FIG. 4 is a top plan view thereof;

FIG. 5 is a bottom plan view thereof;

FIG. 6 is a rear elevational view of the skibinding shown in FIG. 1.
